Primary Examiner — Darlington Ly

(74) Attorney, Agent, or Firm — Craft Chu PLLC;
Andrew W. Chu(57) **CLAIM**

The ornamental design for a knife handle, as shown and described.

DESCRIPTION

1. Knife handle

1.0 is a perspective view of a knife handle showing my new design.

The broken line showing of the knife blade is provided for the purpose of illustrating environmental structure and forms no part of the claimed design.
